UNITED STATES PATENT OFFICE

2,006,440

VACUUM TUBE GENERATOR SYSTEM

Henri Chireix, Paris, France, assignor to Compagnie Generale de Telegraphie sans Fil, Paris, France, a corporation of Germany

Original application April 5, 1926, Serial No. 99,740, Patent No. 1,755,386, April 22, 1930. Divided and this application January 25, 1930, Serial No. 423,308. In France August 10, 1925

15 Claims. (Cl. 250—17)

The present invention relates to improvements in the production of high frequency currents by means of space discharge devices and is a division of my United States Patent Number 1,755,386, 5 patented April 22, 1930.

My invention applies to systems of communication utilizing pure continuous waves or modulated continuous waves.

One of the objects of my invention is to improve the overall efficiency of a communication system by increasing the efficiency of the transmitter itself and the constancy of the wave transmitted.

The novel features which I believe to be characteristic of my invention are set forth with particularity in the appended claims. My invention itself, however, both as to its organization and method of operation will best be understood by reference to the following description taken in connection with the accompanying drawing, in which, I have shown diagrammatically one way whereby my invention may be carried into effect.

In said drawing modulation is affected by the constant current system or the plate control system.

Referring to the drawing, 3 denotes a space discharge device having its input and output circuits coupled in well known manner for the production of oscillations. The condenser 15 and inductance 14 denote the elements adapted and necessary for the generation in device 3 of continuous waves and current sources 1 and 2 denote respectively the plate and filament current sources of device 3.

35 A second space-discharge device 5 is also connected so as to draw its plate and filament current from sources 1 and 2 respectively, said device 5 having its anode connected to the anode of device 3 through a choke coil 4.

40 Tube 5 through the medium of switch 12 is adapted to either act as a modulator tube amplifying signals from a microphone circuit, or as a generator of oscillations. To this end device 5 when switch 12 is in the position 14 has its input and output circuits coupled through the transformer 6 whereby oscillations will be produced at a frequency dependent upon the value of shunted condenser 7. In the figure condenser 8 is intended to provide a negative bias for the grid of device 5. When switch 12 is in the position 13 device 5 acts as a modulator and amplifier tube the input circuit of which comprises a microphone circuit including microphone 10, battery 11, and the primary winding of an audio trans-

former 9 the secondary of which is in the input circuit of device 5.

Energy may be transmitted through an antenna system of any desired kind such as 24 or utilized in any desired circuit. The utilizing circuit may be coupled to the output circuit of space discharge device 3 as shown, or in any well known manner.

The operation of the system is as follows:

When the change-over switch is in the lower position the arrangement is that of a telephony station modulated by plate control, whereas, when the switch 12 is in the upper position device 5 becomes a generator of alternating current whose frequency may be controlled by condenser 15. The potential set up across the terminals of transformer 6 becomes added to that of the source in the plate circuit of device 3.

It is to be clearly understood that there are numerous conceivable modifications of the system the feature resorted to being to use a feed back coupling between the grid and the plate circuits of the modulator tube serving normally for telephony work, with a view to render this valve a self-generator of acoustic frequency currents. The frequency being adjustable by the aid of convenient condensers and inductance coils.

The invention is not limited to the particular applications illustrated and that in fact it is adapted to numerous modifications thereof which may be evolved by those skilled in the art without departing from the spirit and scope of this invention.

I claim:

1. In a space discharge device transmission system comprising a modulator circuit and a microphone circuit, means for effecting transmission of telegraphic signals with modulated continuous waves which comprises means for alternatively establishing a connection between the input of said modulator circuit and said microphone circuit, or a back feed connection between the input and output circuits of the modulator circuit for producing audio frequency oscillations 45 therein, means for controlling the frequency of said oscillations, a radio frequency generator, and means for modulating the radio frequency oscillations produced by said last generator with the audio frequency energy of said modulator circuit.

2. In a transmission system, a radio frequency oscillation generator, a modulator circuit therefor, said modulator circuit comprising a space discharge device having grid and plate circuits,

- means comprising a change-over switch for associating said modulating device input circuit with a microphone circuit when in one position and for coupling said input and output circuits to 5 means for disconnecting said valve from said signaling circuit and associating it with said telephonic circuit to serve as a modulator under the control of the telephonic currents.
5. In a radio system of communication, the combination with an antenna and a circuit having apparatus therein for generating and impressing upon said antenna a wave form carrier current; of a telephonic circuit including a telephonic transmitter; a signaling circuit including 10 means for producing audio frequency wave form signaling current; and means for disconnecting said audio frequency wave producing means from said signaling circuit and associating it with said telephonic circuit to serve as a modulator under 15 the control of the telephonic currents, whereby said carrier current circuit may be alternately associated with said telephonic circuit and with said signaling circuit. 5
6. In a system for transmitting modulated continuous waves, an electron discharge device high frequency oscillator having a plurality of electrodes, an electron discharge device modulator comprising an electron discharge device having 15 a plurality of electrodes, the output circuit of said modulator being coupled to an electrode of said electron discharge device oscillator, a microphone circuit, and switching means adapted in one position to cause said electron discharge 20 device modulator to generate oscillations at a frequency lower than the frequency of oscillations generated by said high frequency discharge device oscillator, whereby the generated relatively low frequency oscillations are applied to 25 an electrode of said high frequency electron discharge device oscillator and in another position to place said modulator circuit under control of said microphone circuit. 10
7. In a radio system of communication, the combination with an antenna and a circuit having apparatus therein for generating and impressing upon said antenna a wave form carrier current; of a telephonic circuit including a telephonic transmitter, a signaling circuit including 15 a thermionic valve for producing audio frequency wave form signaling current; and means for disconnecting said thermionic valve from said signaling circuit and associating it with said telephonic circuit to serve as a modulator under 20 the control of the telephonic currents, whereby said carrier current circuit may be associated at will with either said telephonic circuit or with said signaling circuit. 15
8. In a radio system of communication, the combination with an antenna and a circuit having apparatus therein for generating and impressing upon said antenna a wave form carrier current; of a telephonic circuit including a telephonic transmitter, a signaling circuit including 25 a thermionic valve for producing audio frequency wave form signaling current; and means for disconnecting said thermionic valve from said signaling circuit and associating it with said telephonic circuit to serve as a modulator under 30 the control of the telephonic currents, whereby said carrier current circuit may be associated at will with either said telephonic circuit or with said signaling circuit. 20
9. In a radio system of communication, the combination with an antenna and a circuit having means therein for generating and impressing upon said antenna a wave form carrier current; of a telephonic circuit including a telephonic transmitter; a signaling circuit including 35 a thermionic valve individual to said wave form carrier current circuit and serving as a generator of audio frequency signaling current; and means for disconnecting said valve from said signaling circuit and coupling it with said telephonic circuit to 40 serve as an amplifier of the telephonic currents and to impress such amplified telephonic currents as modulations upon said carrier current circuit. 35
10. In a radio system of communication, the combination, with an antenna and a circuit having means therein for generating and impressing upon said antenna a wave form carrier current, of a transformer secondary winding in said circuit, a telephonic circuit including a telephonic transmitter and a transformer primary winding, a plurality of transformer windings, the first of which is a primary to said secondary winding and the second of which is a secondary to said primary winding, a thermionic valve individual to 45 said wave form carrier current circuit, and means operable at will to selectively connect the input of said valve with either of said plurality of transformer windings. 40
11. In a radio system of communication, the combination, with an antenna and a circuit having means therein for generating and impressing upon said antenna a wave form carrier current, of a transformer secondary winding in said circuit, a telephonic circuit including a telephonic transmitter and a transformer primary winding, a plurality of transformer windings, the first of which is a primary to said secondary winding and the second of which is a secondary to said primary winding, a thermionic valve individual to 50 said wave form carrier current circuit, and 45
12. In a radio system of communication, the combination, with an antenna and a circuit having means therein for generating and impressing upon said antenna a wave form carrier current, of a transformer secondary winding in said circuit, a telephonic circuit including a telephonic transmitter and a transformer primary winding, a plurality of transformer windings, the first of which is a primary to said secondary winding and the second of which is a secondary to said primary winding, a thermionic valve individual to 55 said wave form carrier current circuit, and 50
13. In a radio system of communication, the combination, with an antenna and a circuit having means therein for generating and impressing upon said antenna a wave form carrier current, of a transformer secondary winding in said circuit, a telephonic circuit including a telephonic transmitter and a transformer primary winding, a plurality of transformer windings, the first of which is a primary to said secondary winding and the second of which is a secondary to said primary winding, a thermionic valve individual to 60 said wave form carrier current circuit, and 55
14. In a radio system of communication, the combination, with an antenna and a circuit having means therein for generating and impressing upon said antenna a wave form carrier current, of a transformer secondary winding in said circuit, a telephonic circuit including a telephonic transmitter and a transformer primary winding, a plurality of transformer windings, the first of which is a primary to said secondary winding and the second of which is a secondary to said primary winding, a thermionic valve individual to 65 said wave form carrier current circuit, and 60
15. In a radio system of communication, the combination, with an antenna and a circuit having means therein for generating and impressing upon said antenna a wave form carrier current, of a transformer secondary winding in said circuit, a telephonic circuit including a telephonic transmitter and a transformer primary winding, a plurality of transformer windings, the first of which is a primary to said secondary winding and the second of which is a secondary to said primary winding, a thermionic valve individual to 70 said wave form carrier current circuit, and 65
16. In a radio system of communication, the combination, with an antenna and a circuit having means therein for generating and impressing upon said antenna a wave form carrier current, of a transformer secondary winding in said circuit, a telephonic circuit including a telephonic transmitter and a transformer primary winding, a plurality of transformer windings, the first of which is a primary to said secondary winding and the second of which is a secondary to said primary winding, a thermionic valve individual to 75 said wave form carrier current circuit, and 70

means operable at will to selectively connect the input of said valve with the first of said plurality of transformer windings and open said telephonic circuit or to connect the input of said valve with the second of said plurality of transformer windings and close said telephonic circuit.

12. In a radio system of communication, the combination with a utilization circuit and a generator of high frequency currents for impressing said currents upon said utilization circuit, of a telephonic circuit including a microphone, a thermionic valve serving as a generator of oscillations of lower frequency than said first generator connected in circuit with said first generator, and switching mechanism for connecting said valve to said telephonic circuit for changing the characteristic of said valve from a generator of said relatively lower frequency oscillations to a modulator under control of the telephonic currents.

20 13. In a radio system of communication, the combination with a utilization circuit and a generator for generating and impressing upon said utilization circuit high frequency oscillations, of a telephonic circuit including a telephonic transmitter, a signalling circuit including a thermionic valve individual to said generator and serving as a generator of relatively lower frequency currents, and switching mechanism for disconnecting said valve from said signalling circuit and associating it with said telephonic circuit to serve as a modulator under control of the telephonic currents.

5 a modulator under the control of the telephonic currents.

14. In a radio system of communication, the combination with a utilization circuit and a circuit having means therein for generating and impressing upon said utilization circuit a wave form carrier current; of a telephonic circuit including a telephonic transmitter; a signaling circuit including a thermionic valve individual to said wave form carrier current circuit and serving as a generator of audio frequency signaling current; and means for disconnecting said valve from said signaling circuit and associating it with said telephonic circuit to serve as a modulator under the control of the telephonic currents.

10 15. In a radio system of communication, the combination with a utilization circuit and a circuit having means therein for generating and impressing upon said utilization circuit a wave form carrier current; of a transformer secondary winding in the aforesaid circuit; a telephonic circuit including a telephonic transmitter; a signaling circuit including a primary to the aforesaid transformer secondary winding and a thermionic valve serving as a generator of audio frequency signaling current; and means for disconnecting said valve from said signaling circuit and associating it with said telephonic circuit to serve as a modulator under the control of the telephonic currents.
